Fred Mathews
By Frank J. Thomasson
Atty.

UNITED STATES PATENT OFFICE.

FRED MATHEWS, OF CHICAGO, ILLINOIS.

LOCK FOR FREIGHT-CAR DOORS.

Application filed March 1, 1922. Serial No. 540,146.

To all whom it may concern:

Be it known that I, FRED MATHEWS, a citizen of the United States, residing at Chicago, in the county of Cook and State of

Illinois, have invented certain new and useful Improvements in Locks for Freight-Car Doors, of which the following is a full, clear, and exact description.

My invention relates to means for locking the rear edge of sliding doors and particularly to blind means in the rear vertical member of freight car door-frames that are engaged by the sliding door therefor.

The object of my invention is to provide a locking fixture that is situated in the vertical member of the door-frame and is engaged by the inner surface of the door when the door is being closed and which locks the said rear edge of the same to the vertical member of the door-frame so that the door cannot be burglariously unlocked by lifting it over the guides upon which the door is supported and is adapted to slide. This I accomplish by means hereinafter fully described and as particularly pointed out in the claims.

In the drawings:

Figure 1 is a side view of a sliding freight car door and door-frame, showing a portion broken away to disclose my invention.

Figure 2 is a horizontal section through a broken away rear portion of a sliding freight-car door and the stanchion of the adjacent broken away portion of the door-frame.

Figure 3 is a side view of the lock attached to a portion of the stanchion of the door-frame.

Figure 4 is a side view of the lock looking at it at right angles to the view shown in Figure 2.

Figure 5 is a side view of the counter-plate of the lock.

Referring to the drawings A represents the rear vertical edge of a door-frame, of a freight-car, and B represents the rear portion of a sliding door for closing the doorway, and both of these elements are of the usual or of any preferred construction, whose upper edges are provided with hangers a, that have grooved wheels, that travel on an overhead track or tram, (not shown), and whose lower edge is held against the car and guided by guides c, of the usual construction.

At a certain point above the sill of the

door the outer angle or corner of the rear vertical member of the door-frame is cut away to form a suitable recess in which the frame of the lock is inserted. This frame, 3, consists, preferably, of a vertical U-shaped strip of metal, the ends, 4, of the parallel portions of which are flanged vertically and provided with screw or rivet holes 5, by means of which it is secured in position with the parallel portions thereof horizontal. A vertical pivotal pin 6 is thrust through suitable openings in the parallel portions of the frame, 3, and its ends swaged or headed, and upon this pin the boss, 7, of the lock is loosely mounted. This lock consists of a somewhat L-shaped arm, 8, that projects from the upper portions of the boss, 7, toward the door B, the inner surface of which latter is adapted to engage the same, substantially as hereinafter explained. The lower edge 9, of the boss 7, commencing from the under edge of the arm 8 extends downwards and is bevelled. This bevelled portion terminates in a vertical shoulder 10, which, when the arm is at the lower limit of its vertical reciprocal movement, is adapted to engage shoulder, 11, of a stationary seat, 12, whose upper edges 13, is bevelled to correspond to the bevel 9 of the lower edge 85 of the boss 7, of arm 8.

The counterpart for arm 8 of the lock is made by providing the inner surface of the door, near the rear vertical edge thereof, with a recess 14, and providing a rectangular counter-plate 15, that covers the same and is secured in place by rivets or bolts, 16, tapped through the openings near the corners of the counter-plate and into or through the door. The rear edge, 17, of the counter-plate, 15, is bent inwards and enters the recess in the door, and said counter-plate is provided with a rectangular opening 18, the edge of which farthest from edge 17, is provided with a tongue, 19, that is bevelled outwards into the recess, 14.

A coil expansion-spring 20, is placed upon the pivotal pin 6, above the arm 8 and normally keeps the same depressed at the lowest limit of its vertical movement, so that, when said arm is not pressed inwards by the door, the lower bevelled end of the boss of arm 8 engages the correspondingly bevelled edge 13 of the stationary seat and is caused thereby to swing outwards, and in this position the arm 8 will occupy the recess 14, and be under the rear edge of the opening in the

counter-plate, and when the door is locked will hold the rear edge of the door against the rear stanchion of the door-frame. When the door is unlocked and it is slid to the rear, the tongue 19 of the counter-plate comes in contact with the bevelled edge of the L-shaped arm 8, and pushes it out of the recess 14 and thus unlocks the rear edge of the door. The width of the opening 18 of 10 said counter-plate corresponds to the width of the arm 8, plus its vertical movement, and when it is out of the recess 14 the arm 8 will be at the limit of its upward movement. Only when arm 8 enters the counter-plate 15 and recess will spring 20 push it downwards and rotate it so as to come in the locking position shown in Figure 1 of the drawings.

What I claim as new is:

1. The combination with the frame of a 20 doorway and a lock secured in a vertical member thereof, of a sliding door for closing the doorway and a counterpart for said lock in its inner surface out of which the lock is kept by said door when the latter is 25 opened, and which interlocks therewith when the door is closed.

2. The combination with the frame of a 30 doorway, and a lock secured in a vertical member thereof including a laterally oscillatory arm, of a sliding door for closing the doorway and having a counterpart in its inner surface out of which the arm is kept by the door when the latter is open, and which interlocks therewith when the door is closed.

3. The combination with the frame of a 35 doorway, and a lock secured in a vertical member thereof including a laterally oscillatory L-shaped arm, of a sliding door for closing the doorway and having a counterpart in its inner surface out of which the arm is kept by the door when the latter is open, and which interlocks therewith when the door is closed.

4. The combination with the frame of a 45 doorway, and a lock secured in a vertical member thereof including a laterally oscillatory L-shaped arm, of a sliding door for closing the doorway and having a counterpart in its inner surface one end of which is overshot out of which the arm is kept by the door when the latter is open, and which interlocks therewith when the door is closed.

5. The combination with the frame of a 55 doorway, and a lock secured in a vertical member thereof that includes a normally de- 60 pressible oscillatory L-shaped arm, of a sliding door for closing the doorway, and a counterpart for said lock in its inner surface one end edge of which is overshot out of which the lock is kept by said door when the latter is opened, and which interlocks therewith when the door is closed.

6. The combination with the frame of a 65 doorway, and a lock secured in a vertical

member thereof that includes a normally de- 65 pressible oscillatory L-shaped arm, of a sliding door for closing the doorway, and a counterpart for said lock in its inner surface one end edge of which is overshot and the 70 opposite end bevelled out of which the lock is kept by said door when the latter is opened, and which interlocks therewith when the door is closed.

7. The combination with the frame of a 75 doorway, a U-shaped frame sunk into a vertical member thereof, an axial pin the ends of which are in the parallel portions of said U-frame, and an L-shaped arm mounted on said pin and projecting toward said door, of a door, and a counterpart in the inner surface thereof one end of which is overshot and out of which the arm is kept by said door when it is open, and that interlocks therewith when the door is closed.

8. The combination with the frame of a 85 doorway, a U-shaped frame sunk into a vertical member thereof, an axial pin the ends of which are in the parallel portions of said U-frame, an L-shaped arm mounted on said pin and projecting toward said door and the pivotal boss of said arm projecting downwards and its lower edge bevelled and adapted to engage the correspondingly bevelled edge of a stationary boss made integral with the lower parallelled portion of said 95 U-shaped frame.

9. The combination with the frame of a 100 doorway, and a lock secured in a vertical member thereof including a laterally oscillatory L-shaped arm, of a sliding door for closing the doorway and having a counterpart in its inner surface comprising a recess and a plate covering the same that has an opening therein one end edge of which over- 105 shoots said recess and out of which the arm is kept by the door when the latter is open, and which interlocks therewith when the door is closed.

10. The combination with the frame of a 110 doorway, and a lock secured in a vertical member thereof including a laterally oscillatory L-shaped arm, of a sliding door for closing the doorway and having a counterpart in its inner surface comprising a recess and a plate covering the same that has an opening therein one end edge of which over- 115 shoots said recess and the other end of which has a tongue that is bent inwards to provide a bevel, and out of which the arm is kept by the door when the latter is open, and which interlocks therewith when the door is closed.

In witness whereof I have hereunto set my hand this 21st day of February, 1922.

FRED MATHEWS.
